Henry Howison

United States Patent Office.

J. W. LORAIN, OF PHILADELPHIA, PENNSYLVANIA.

Letters Patent No. 80,752, dated August 4, 1868.

IMPROVEMENT IN HANGERS FOR SHAFTING.

The Schedule referred to in these Letters Patent and making part of the same.

TO ALL WHOM IT MAY CONCERN:

Be it known that I, J. W. LORAIN, of Philadelphia, Pennsylvania, have invented an Improvement in Hangers for Shafting; and I do hereby declare the following to be a full, clear, and exact description of the same.

My invention consists of certain improvements, fully described hereafter, in hangers for shafting, by which improvements the ready adjustability of the hanger to its proper position is effected.

In order to enable others skilled in the art to make and use my invention, I will now proceed to describe its construction and operation.

Figure 1 is a vertical section of my improved hanger.

Figure 2, a vertical section on the line $x x$, fig. 1, and

Figure 3 a sectional plan on the line $1 2$, fig. 1.

Similar letters refer to similar parts throughout the several views.

My improved hanger consists of five main parts, namely, the permanent casting A, secured to the beams or rafters by bolts passing through holes a in the plate b ; the plummet B, suspended from the latter; the portion D, and the upper and lower bearings E E', carried by the said portion, and the cap F. A segment, e , of a sphere is formed on the under side, at the middle of the bearing E', and a similar segment, e' , on the upper side of the upper bearing, the segment of the lower bearing being adapted to a socket of a corresponding form in the adjustable portion D of the hanger, and that of the upper bearing to the cap F, which has in front a lip, f , corresponding to a lip, h , on the portion D of the hanger, a recess in the latter admitting a lip or projection, i , at the rear of the cap.

There is on the permanent portion A of the hanger, a projection, m , the point of which must be in a line $x x$ drawn through the point of suspension of the plummet B, and through the centre of the bearing, and the line t of junction, between the two portions A and D of the hanger, must be parallel with the said line $x x$. As seen in fig. 2, the point of the projection m must be in a line, $y y$, drawn from the point of suspension of the plummet through the centre of the spherical socket which receives the bearings.

In securing to the beams or rafters of the ceiling the portion A of the hanger, no other precautions are necessary than that of so adjusting it that the point of its plummet shall coincide with the point of the projection m , precise vertical adjustment being unnecessary, as this can be accomplished, after securing the portion A, by so operating the set-screw p as to raise or lower the adjustable portion D of the hanger to the desired extent, after which the two main portions of the hanger may be permanently secured together by tightening the nuts of the bolts g .

As the portion D of the hanger is, during its adjustment, guided by the slots through which these bolts pass, and as the line of junction between the two portions A and D of the hanger is parallel with the line $x x$, the centre of the bearing must always be in this line, no matter to what point the portion D may be adjusted.

It will be seen, without further description, that a number of hangers thus constructed may be quickly secured to their places and readily so adjusted that the centres of their bearings may be in proper line with each other, and that any departure of the hangers from their proper positions, consequent on lengthened use and the strains to which they are subjected, may be at once ascertained by examining the position of the point of the plummet in respect to the projection m , for the non-coincidence of the two must be a certain indication that the portion A of the hanger requires readjustment.

The plummet and projection m may be employed to advantage in connection with ordinary hangers which have no adjustable portion D, although the hanger described is preferable for reasons given above.

The bearings E and E' can be readily removed and replaced, all that is necessary for detaching the cap F being the withdrawal of the single bolt from the lips f and h .

I claim as my invention, and desire to secure by Letters Patent—

1. The combination, with a hanger, of a plummet B and projection m , the latter being arranged in respect to the centre of the bearing and the point of suspension of the plummet, as set forth for the purpose specified.

2. The within-described hanger, composed of the permanent portion A, with its plummet B and projection m, and the adjustable portion D, carrying the bearings E and E', the whole being combined and arranged substantially as and for the purpose described.
3. The cap F, arranged to confine the bearings E and E', secured in front to the portion D of the hanger by a bolt or screw, and fitting at the rear in a recess in the said portion D, all substantially as and for the purpose herein set forth.

In testimony whereof, I have signed my name to this specification in the presence of two subscribing witnesses
